UNITED STATES PATENT OFFICE.

WILLIAM H. HART, OF NEW BRITAIN, CONNECTICUT.

DESIGN FOR A STRAP-HINGE.

SPECIFICATION forming part of Design No. 23,257, dated May 8, 1894.

Application filed April 10, 1894. Serial No. 507,043. Term of patent 14 years.

To all whom it may concern:

Be it known that I, WILLIAM H. HART, a citizen of the United States, residing at New Britain, in the county of Hartford and State 5 of Connecticut, have invented and produced a new and original Design for a Strap-Hinge, of which the following is a specification, reference being had to the accompanying drawing, forming part thereof, in which the figure 10 is a front elevation of a strap hinge showing my design.

A designates one leaf having the knuckle 2 with its end extended on the body of the leaf and provided with a rounded tongue or end 15 3, as shown, in which the screw hole 4 is formed. The leaf B has its knuckle tongues 5 projecting from the knuckle with the ends 6 rounded as shown, and with the screw hole

7 in said ends. Both leaves have an elongated opening cut therefrom, the opening 8 20 in the leaf A being divided or forked at its broader end and extending along each side of the tongue 3, as 9, 9. The opening 10 in the leaf B has a narrower rounded recess 11 at the wider part of the leaf, as shown. 25 At both of the openings 8 and 10, the leaves are provided with inwardly projecting wings 12 curved on their edge and adjacent to said wings are the screw holes 13.

What I claim is—

The design for a strap hinge, substantially as herein shown and described.

WM. H. HART.
